UNITED STATES PATENT OFFICE.

VICTOR VON FRANKENBERG, OF PINE BLUFF, ARKANSAS.

TUNING-PIN FOR MUSICAL INSTRUMENTS.

SPECIFICATION forming part of Letters Patent No. 399,712, dated March 19, 1889.

Application filed June 11, 1888. Serial No. 276,889. (No model.)

To all whom it may concern:

Be it known that I, VICTOR VON FRANKENBERG, a citizen of Silesia, Germany, residing at Pine Bluff, in the county of Jefferson and State of Arkansas, have invented a new and useful Tuning-Pin for String-Instruments, of which the following is a specification.

My invention relates to improvements on tuning-pins for string-instruments; and the objects of my invention are, first, to provide the finest tuning of a string in any desired pitch; second, to keep this tuned string up to its pitch for the longest possible time; third, to enable even the unskilled mechanic to bring the string back to its original pitch without depending on his hearing alone. I attain these objects by the mechanism illustrated in the accompanying drawings, in which—

20 Figure 1 is a view of the pin only; Fig. 2, a sectional inside view of its head-screw; Fig. 3, a sectional inside view of its tube or cap; Fig. 4, the wrench-like tuning-key to be used in connection with it; Fig. 5, a perspective 25 view of the whole pin with tube or cap, head-screw, and string attached as fixed in an instrument; Fig. 6, a part perspective view of the upper part only, showing the handling of the head of the tube or cap with the tuning-key, at the same time allowing the head-screw to be turned down as far as possible.

Similar letters refer to similar parts throughout the several views.

The pin Fig. 1 consists of three parts—C, 35 its square foot, to be fixed in a corresponding hole wherever convenient in the instrument, so as to prevent a turning of the pin; B, the thread part for the corresponding tube or cap in Fig. 3 turned to the right; A, the somewhat 40 smaller head part of the pin with the thread part for the corresponding head-screw in Fig. 2 turned to the left.

The head-screw Fig. 2 consists of three parts—A, the corresponding thread part to the 45 thread part A on Fig. 1; W, two wings, serving as handles to turn the head-screw; N, a nose supposed to indicate on the table T of Fig. 3 a removal of either head-screw or tube.

The tube or cap Fig. 3 has four parts—B, 50 the corresponding thread part for the thread part B in Fig. 1; D, the head of the tube or cap, polygonal to enable the turning of the

tube by using a tuning-key, as per Fig. 4; T, the top of the tube's head, supposed to serve as table for the nose-marks indicating the 55 proper pitch; K, a knob with a hole in which to fasten the string.

The tuning-key Fig. 4 wrench-like, to be used for turning the tubes head, adjustable from the side of same; E, the arms to grasp 6c the head; F and H, the handle and knob, the latter movable on the handle to allow a convenient position of the tuner's hand and arm while turning with it.

Fig. 5 shows with its numbers and letters 65 of the similar detail parts the tuning-pin complete, with string attached to be tuned in pitch.

Fig. 6 illustrates the upper part of the pin complete, with tube and head-screw, the latter 70 being turned down, tied to the table of the tube's head D, while the tuning-key yet holds the tube in its position.

I carry out the operation of tuning in the following way: Suppose the tuning-pin stands 75 as per Fig. 5 in the instrument, the string attached but yet loose. I apply the tuning-key, Fig. 4, from the most convenient side to the head of the tube, turning same to the right (the tube thus winding up the string) till the 80 string is in its most proper pitch. When this is reached, I yet hold the tuning-key steady and turn the head-screw, Fig. 2, down on the tube's head as tight as possible. Some little pinchers may help enforce this. Then the 85

key can be taken off, and the mark on the side of the nose can be scratched on the table T, indicating now the only possible point where the string can be in proper pitch, the least removal of either tube or head-screw having 90 a different pitch of the string as a result, so that even the non-mechanic, advised in that direction by a catalogue or salesman, can easily discover a change in pitch in looking whether the nose N yet stands on its mark, 95 and if it does not so, can easily adjust it again on its proper place—in other words, can tune the string again without depending only on his hearing. Nevertheless this will be necessary only accidentally, as the two thread 100 parts of head-screw and tube being turned, as stated, in contrary direction will, when meeting on the table T, act as two wedges upon each other, thus securing the longest

possible standing of the tube, or with this of the string in its once reached position or pitch.

I am aware that tuning-pins are used in any string-instrument without or with screw parts attached, as on the Mason and Hamlin pianos, on some bass-violins, guitars, &c., also that screws with different thread parts cut in opposite direction may exist; but

10 What I do claim as my invention, and desire to secure by Letters Patent, is—

1. A tuning-pin provided with the square foot C, middle part, B, and head part A, the parts A and B being of different sizes and 15 having their threads cut in opposite directions, for the purpose set forth.

2. The combination, with a tuning-pin, of a head-screw, having wings W, threaded part A', and nose N, for the purpose set forth.

3. The combination, with a tuning-pin having foot C, middle part, B, and head part A, the last two parts being of different sizes and having their threads cut in different directions, of a tube having a polygonal head, D, top table, T, threaded part B', and knob K, 20 and a head-screw consisting of threaded part A', wings W, and nose N, as and for the purpose specified.

VICTOR VON FRANKENBERG.
